ANTHONY P. MILLER, OF PLEASANTVILLE, NEW JERSEY

METHOD OF FORMING PILING

Application filed May 3, 1929. Serial No. 360,135.

The present invention is concerned with a method of installing mushroom piling, and while capable of a wide range of utility is particularly concerned with the installation 5 of such piling in fine water-bearing sand, such, for instance, as beach sand.

It is well recognized that fine sand, particularly water-bearing sand, presents peculiar problems insofar as excavation work of any 10 kind is concerned. If the sand is saturated with water it will run and drift freely and it is difficult to work in such sand without using some method of enclosure to prevent the sand from filling the excavation.

Attempts have been made to overcome 15 these difficulties and to devise methods of installing concrete mushroom piling in water bearing sand without the use of sheathing and by the expedient of lowering the water level in the sand to the line of the proposed piling excavation, then digging down 20 to the water level and continuing to dig until the wet sand at the bottom of the hole forms a mushroom by its natural running 25 and caving action. Such a method, disclosed in the prior patent to Ferry & Miller, No. 1,593,445, dated July 20th, 1926, has proven unreliable in practice.

One of the principal difficulties of the 30 method is the fact that when a well-point system is used to lower the water level over a predetermined area in which it is proposed to install a series of pilings, the water level in the sand is never horizontal. That 35 is to say, the capillary action of the fine sand results in the creation of a water level which gradually slopes from the well points towards the center of the area to be dried. This condition of a sloping water level in 40 the sand results in the formation of an extremely lop-sided mushroom since the excavation will tend to unduly cave at the side nearest the higher water level point and will fail to cave at the side nearer the lower water level point.

A contributory factor here is the water 45 flow toward the well points, which even assuming a nearly horizontal water level will wash sand from one side of the mushroom toward the other, thereby causing caving

at one side and filling in at the other with a resultant tendency toward lop-sidedness.

Even assuming therefore that all mushroom pilings of a set could be simultaneously sunk and installed while the water level 55 remains stationary, all of these pilings would have lop-sided mushrooms impairing not only their ability to resist compression but their ability to serve as anchorages 60 for a superimposed building structure.

With such an eccentrically loaded footing the slightest settlement in the base would cause a bending moment in the pillar or fracture the pillar adjacent the mushroom or cause it to shear off at the mushroom. 65 The eccentricity of the mushroom would be difficult to detect even though the engineers maintained a careful inspection on the job and the fracture of several pilings in one footing would of course create a very serious 70 and dangerous condition.

As a practical matter the water level can never be maintained at exactly the point desired. The well points are always working and tending to lower the water level, whereas 75 the pilings are installed successively and not simultaneously. The result is that the bottom of one mushroom piling will be at one level and the bottom of the next one will be at a level considerably below it, due not only 80 to the sloping water level but to the continuously lowering water level in the sand. The result of this condition is that large margins of safety must be figured in constructing pilings. The liner shells which are used 85 for the pillar molding shafts of the piling excavations are never of the right length. A superimposed structure will be better supported at certain points than it will at others. The cost of construction and the materials 90 for any given installation can never be accurately calculated in advance.

The pressure at the base of the piles distributes itself downwardly through the soil at an angle of approximately 60° (in beach 95 sand). The piles when used for foundation footings are placed close together. In consequence the pressure through the soil from the higher piles would be transmitted to the mushroom of certain of the lower piles, in 100

creasing the load thereon and increasing the unit stress below the base. As a result of this condition soil areas where pressure is greatest will have a greater tendency to settle. In many instances a single mushroom may be carrying at one side part of the load of a higher mushroom of an adjacent pile, while at its opposite side it carries only its own load, and any tendency to settling would readily fracture this mushroom.

Another very considerable disadvantage of the patented method is the fact that by such method concrete is poured into the saturated sand at the bottom of the mold in order to form the completed piling. When this heavy material is poured into place the sand at the bottom of the mold splashes and runs, some of the concrete sinks into the sand, the carefully prepared mushroom bottom of the mold is broken down, additional sand shales off or caves in on the concrete and the final result is a lop-sided mushroom of non-homogeneous formation, and consisting simply of a plurality of loosely separated concrete fragments having no coherence and little structural strength.

Another disadvantage of the prior methods has been the fact that neither the size nor the shape of the mushrooms have been uniform and even the most careful practice of prior methods has failed to insure any real uniformity in mushroom sizes and shapes, much less in length of pillars or in load sustaining ability.

In accordance with the present method I overcome all of the above noted difficulties in that I render the depth of the piling excavations independent of the water level in the sand, produce symmetrical mushroom enlargements at the bottom of the excavations, install a series of pilings of equal depth and structural strength and produce a homogeneous concrete mushroom anchorage at the bottom of the piling.

In carrying out the method I reduce the water level in the sand to a point below the depth of the proposed piling excavation and maintain it below such depth in the entire area where piling is to be installed. The vertical bore of the piling excavation is then drilled to any desired depth which may be accurately determined by prior engineering calculations.

Having drilled the vertical bore I insert a metal liner or shell, this shell being preferably of a novel construction which permits it to be readily slipped up and down, in the bore until it reaches exactly the proper position. Shells of standard size may be used inasmuch as the exact bore length is always known in advance before excavation is started and in no manner dependent on or controlled by variations in the water level in the sand.

In order to form the mushroom enlarge-

ment I partially fill the bore with water up to a definite and predetermined level, I then introduce an agitating tool and agitate the otherwise inner body of water which is slowly draining through the sand toward the artificially produced lower water level. The water agitation whether it be in the nature of a vertical wave action or a swirling motion or a combination of both will tend to scour away or erode the sand walls of the unlined lower portion of the bore, thereby radially enlarging the upper portion of the unlined lower end of the bore and gradually filling up the bottom thereof with the sand displaced and washed down by the scouring. With each stroke or revolution as it may be of the agitating means that lateral portion of the sand wall of the bore which is in contact with the water will be radially enlarged. Similarly at each stroke or revolution the level of the body of water will be lowered due first to the progressively increasing bore diameter and second to the water drainage through the sand.

Agitation is preferably stopped while a certain amount of water still remains in the bottom of the hole, this water acting as it drains out through the sand to leave a symmetrically rounded bottom for the mushroom enlargement which has been produced by the scouring or eroding action. The sand which is washed away to form the enlargement fills in at the bottom of the shaft so that the bottom of the final mushroom mold will be considerably above the bottom of the original shaft excavation.

A feature which contributes to symmetry and accurate size determination is the fact that no excavating operations are performed except the initial drilling of the shaft or bore. Uniformity of size is assured by the simple expedient of accurately determining (1) the depth of the bore (2) the amount of water poured in and (3) the duration of agitation. Obviously no great skill is required for accurate determination of these controlling factors.

Having produced the mold for the piling, powdered concrete is gently sprayed or sifted into the mold so that the sand mold walls will not shale off or break down. This concrete, taking up the moisture from the walls of the mushroom mold, rapidly hardens and forms a homogeneous concrete mass unmixed with sand. Where the mold is not sufficiently wet at its bottom to moisten the concrete, supplementary moistening agents may be introduced through the bore.

Having thus formed the mushroom the piling is completed by pouring concrete into the shell to form the pillar, the substantially hardened mushroom base thereby integrally uniting the pillar and mushroom in one substantially homogeneous structure. The shell lining of the bore of course prevents admix-

ture of the concrete with the sand at this point.

This method not only permits the load carrying ability of a piling to be accurately calculated in advance, and insures the installation of pilings of uniform size and length having much greater strength than any piling which can be produced by the old method, but obviates the necessity for making frequent tests to determine the water level in the sand. It also advantageously permits deep well water-lowering apparatus such as is disclosed in my copending application, Serial No. 224,206, filed October 5th, 1927, to be used, and the water level lowered over a wide area by a single pump, as opposed to conventional methods in which numerous well-points, hose lines and other complex apparatus encumber the field of operation and seriously interfere with the expeditious carrying out of the work.

This application is a continuation in part of my copending application, Serial No. 320,813, filed Nov. 21, 1928.

The invention may be more fully understood from the following description in connection with accompanying drawing which is a diagrammatic broken vertical sectional view showing a pair of deep well pumps in position to lower the water level throughout a considerable area and showing from left to right three successive stages or steps in the fabrication of a piling.

In the drawing the normal water level in the sand is shown by the dot-and-dash line α — α . The first step of the method is to lower this water level to a point which in the area of operations is below the proposed bottom of the piling excavations, the new lowered water level being shown at y — y and sloping somewhat due to the capillary action of the fine sand.

I may use ordinary suction well points for this purpose but I prefer to use deep well pumps such as those illustrated. Each of these pumps includes a casing 11 having a screen 12 and the drill point 13 at its lower end. Rotary force pump 14 disposed within the casing 11 is connected by an operating shaft 15 to a motor 16 mounted on top of the casing 11 and the water forced upwardly by the pump is carried off to discharge by the pipe 17. In practice a single pump of this nature, if sunk deeply enough will serve to reduce the water level over a large area, but I have shown two of the pumps in operation in the drawings.

The drawings show from left to right three successive stages in the construction of the piling, these

The drawing shows from left to right three successive stages in the construction of the piling, these stages being for the convenience of description lettered A, B and C.

Having lowered the water level I sink a

vertical bore, or shaft 18 in sand preferably using an ordinary auger 10 to form the excavation. The next step is to insert the relatively light gauge metal shell 19 into the bore to a point where the top of this shell is substantially at the surface level of the sand. This shell is preferably provided with a slightly flaring entering mouth 20 which scales and trims the walls of the bore 18, shaving some of the sand off of the walls and causing it to fall into the bottom of the excavation. The purpose of this flare is to permit the ready adjustment of the shell in the bore to exactly the proper height and to prevent the shell from becoming so firmly frictionally held in the sand bore that it cannot be moved either up or down. When the shell is once properly adjusted sand is sifted into the annular space between shell body and shaft wall, so that the shell is firmly held in position.

After emplacing the shell or liner the next step is to enlarge the bottom of the shaft or bore 18 to form a sand mold for the mushroom, bulb, or pedestal portion of the piling. Numerous expedients may be resorted to in this connection, but I preferably employ a special enlarging process of my own invention. This process consists generally of partially filling the bore with water and then agitating the otherwise inert body of water to erode or wash away the sand at the lower end of the bore. As an incident of such agitation the bottom of the bore becomes partially filled with the sand which has been eroded from the bore walls immediately below the metal shell and the bottom of the final mold is well above the bottom of the original shaft 18.

Preferably enough water is poured to fill the bore up to approximately the lower end of the shell, the water being poured from bucket 22 or in any other suitable manner. That portion of the drawing indicated generally at "A" depicts the partially completed mold after the shaft has been sunk, the liner emplaced, and the water poured in to the desired level.

As suggested above numerous modes of water agitation might be employed. Preferably, however, the agitation is mechanically accomplished, one convenient method being simply to introduce the auger 10 and vertically reciprocate it by hand. This action sets up a wave motion in the body of water which so far as I have been able to determine is somewhat complex. It includes a vertical water flow along the walls of the bore and at the same time somewhat of a swirling action due to the effect of the spiral auger blade. In that portion of the drawing designated at "B" I have shown the water agitation method in progress and have also shown on a much exaggerated scale in dotted lines a rather crude diagram of the changing shape of the

5 mold after each reciprocation of the auger. What apparently happens is that the water scours away a thin annular film of sand from the wall of the bore at each reciprocation of the auger and this sand deposits in the bottom of the bore. Each succeeding wave action takes effect on a wall section of decreased length. This is due to the fact that the water level is constantly lowered as the bore is enlarged and the bottom of the hole is constantly rising as the sand which has been washed away flows into the bottom of the hole. Lowering of the water level is further expedited by the seepage of the water into 10 the sand down to the artificial water level at $y-y$.

15 After this agitation has been carried on to the desired extent the auger is preferably withdrawn leaving some water still in the bottom of the hole. This water causes the sand bottom of the mold to assume a curvature in accordance with the well known running angle of saturated sand. The upper general conical portion of the mold has walls 20 sloping at the well known caving angle of sand and these sloping walls will either run directly in the bottom of the mold or may be connected to the bottom of the mold by a general vertical wall portion (not shown) in 25 accordance with the extent to which agitation of the water has taken place (note varying mold shapes shown in dotted lines at "B").

30 My experiments to date lead me to the conclusion that the particular method of agitating the otherwise inert body of water is subject to considerable variation without materially changing the efficacy of the method. In other words while a reciprocating screw 35 auger gives a combined up and down and swirling motion to the water I believe that any other instrumentality for giving either this combined action or giving either the swirling or the up-and-down motion independently would serve the purpose. As typical of other instrumentalities that might be used I may mention conventional motor driven or manually operated rotary or reciprocatory agitators of various types.

40 There is shown at "C" the complete mold after the water has drained out of it and prior to the introduction of the concrete or cementitious piling material.

45 At this time unless the sand in the bottom of the mushroom is given time to dry, it will be apt to splash if concrete is poured in upon it. Furthermore this sand will be so soft that poured concrete would tend to sink into it. I therefore complete the formation of the 50 co piling by sifting, spraying or otherwise gently introducing powdered cement or concrete into the mushroom, this concrete soaking up the moisture from the sand, or if desired, being moistened by additional water 55 being poured into the shell until it forms a

homogeneous, bulbous pedestal structure 24 conforming to the shape of the mushroom sand mold. This structure having substantially hardened, the piling is completed by pouring concrete into the shell to form the 60 final stem or pillar 25 of the piling.

65 The important feature about sifting, spraying, or otherwise gently introducing a preferably dry and powdered cement into the enlarged bottom of the excavation is the 70 fact that the material and its method of introduction militate against shaling off or breaking down of the sand walls of the mold.

75 If the pillar-forming concrete is poured in onto the cement mushroom just before the 80 latter is completely hardened, the pillar and mushroom will be integrally welded together into one substantially homogeneous strong mass.

85 It will of course be apparent that in many instances it is not necessary to completely fill the mushroom mold with the cementitious dry mix. Where the mold is comparatively dry and hard, as it may sometimes be in fairly coarse sand, concrete pouring may be 90 safely resorted to. On the other hand, where sand is fine, so that the water which has been used in forming the mushroom does not flow off quickly or freely, the dry mix may be used to absorb the water and then the wet concrete immediately poured in upon it, making the base partly a dry mix and partly a wet mix. In other words, the exact nature of the sand in which the work is being carried out will be the determining factor in the extent 95 to which the dry mix must be used. It is more or less optional whether the pillar is poured while the concrete of the base is still green or after it is partially hardened. By using the former method, however, the 100 weight of the concrete in the pillar tends to compact the concrete in the base and force it tightly against the mushroom mold.

105 What I claim is:

110 1. A method of forming a mold for a mushroom piling in water bearing sand which includes the steps of artificially lowering the water level in the sand below the proposed bottom of the piling excavation, sinking a 115 straight shaft which terminates above the lowered artificial water level filling the shaft with water to a height at least equal to the top of the proposed mushroom and agitating the otherwise inert body of water while the latter is draining through the sand to effect 120 erosion of sand from the walls of the mold and deposition of such sand in the bottom of the mold.

125 2. A method of field-fabricating concrete pedestal pilings in water bearing sand which includes the steps of sinking a straight shaft the bottom of which is above the water level in the sand at the time the shaft is sunk, partially filling the bottom of the shaft with water to a level at least as high as the top of 130

the proposed mushroom and while the water is seeping out of the shaft through the sand agitating the otherwise substantially inert body of water to scour away part of the wall of the shaft, said scouring being accompanied by the depositing of the eroded sand in the bottom of the shaft whereby the bottom of the shaft is raised and an enlargement of the shaft is formed then filling the sand mold thus formed with concrete.

3. A method of forming a mold for mushroom piling in beach sand which includes the steps of artificially lowering the water level in the sand below the proposed bottom of the piling excavation, sinking a straight shaft which terminates above the artificially lowered water level, filling the shaft with water to at least the height of the top of the proposed mushroom and so agitating the otherwise inert body of water while the latter is seeping through the sand as to set up a vertical wave motion along the walls of the shaft, causing erosion of the sand from the walls of the shaft and deposition of the eroded sand in the bottom of the shaft.

4. A method of forming a mold for mushroom piling in beach sand which includes the steps of artificially lowering the water level in the sand below the proposed bottom of the piling excavation, sinking a straight shaft which terminates above the artificially lowered water level, filling the shaft with water to at least the height of the top of the proposed mushroom and so agitating the otherwise inert body of water while the latter is seeping through the sand that a swirling impetus is imparted to the water to effect erosion of the sand from the lower portion of the shaft walls and the forming of an enlargement at the bottom of the shaft.

5. A method of forming a mold for mushroom piling in beach sand which includes the steps of artificially lowering the water level in the sand below the proposed bottom of the piling excavation, sinking a straight shaft which terminates above the artificially lowered water level, filling the shaft with water to at least the height of the top of the proposed mushroom and so agitating the otherwise inert body of water while the latter is seeping through the sand as to effect a compound swirling and vertical wave motion causing erosion of sand from the walls of the mold and deposition of eroded sand in the bottom of the mold.

6. A method of forming a mold for a mushroom piling in water bearing sand which includes the steps of sinking a straight shaft the bottom of which is above the water level in the sand at the time the shaft is sunk and below the proposed bottom of the mushroom mold, lining the upper portion of the shaft with a metal shell, filling the shaft with water to a level at least as high as the top of the proposed mushroom and while the water

is seeping out of the shaft through the sand, agitating the otherwise substantially inert body of water to scour away the unlined part of the wall of the shaft, said scouring being accompanied by a deposition of eroded sand in the bottom of the shaft whereby the bottom of the shaft is raised as an enlargement of the shaft is formed.

7. A method as set forth in claim 6 and wherein the liner shell is of thin gauge material inserted without driving and without the use of a core and is provided with a flaring entering end to shave and trim the walls of the mold and facilitate forcing in of the shell to the desired extent and in which the annular space around the shell produced by cutting away of sand as an incident of inserting the shell is refilled with sand to frictionally hold the shell in place and prevent it from slipping into the subsequently formed mushroom mold.

Signed at Atlantic City in the county of Atlantic and State of New Jersey this 1st day of May A. D. 1929.
